CLAIM

The ornamental design for an inch-metric screw gauge, as shown and described.

DESCRIPTION

FIG. 1 is a front elevational view of an inch-metric screw gauge illustrating my new design therefor;

FIG. 2 is a top elevational view thereof, the bottom view being the same;

FIG. 3 is a sectional view taken along line 3—3 of FIG. 1, to better show my design;

FIG. 4 is a side elevational view thereof, the opposite side being identical; and,

FIG. 5 is a rear elevational view thereof.
